GARMENT PRESSING MACHINE

Herbert G. Beede, Pawtucket, R. I.

Original application August 12, 1931, Serial No.
556,694. Divided and this application March
27, 1935, Serial No. 13,331

5 Claims. (Cl. 74—539)

My invention relates to garment pressing machines such as are used in tailoring, dry cleaning, laundering and similar establishments for steaming and pressing clothing of various kinds, and 5 the invention relates particularly to latching mechanism for holding the pressing elements closed and for releasing the latching mechanism so that the movable pressing element can move to open position.

10 This application is a division of my prior application, Ser. No. 556,694, filed August 12, 1931, upon which Patent No. 2,034,279 was issued March 17, 1936, and the objects of the invention include, first, the provision of latching mechanism automatically operable upon closing of the 15 press to releasably maintain the pressing elements in pressing position; second, the provision of means for effecting release of the latching mechanism to allow the pressing elements to return to open position either in combination 20 with the means for effecting closing of the press or by independent means operable from convenient points by the hand or foot of the operator.

25 All of the objects and advantages of the invention will become apparent and will be referred to during the course of the following detail description of the accompanying drawings wherein are shown preferred embodiments of the invention and in which,—

Fig. 1 is a side elevation of a portion of a pressing machine with parts in section showing one form of my present invention applied thereto;

35 Fig. 2 is an enlarged fragmentary perspective view of a portion of the releasing mechanism;

Fig. 3 is a perspective view of a pressing or ironing machine showing another form of the invention applied thereto;

40 Fig. 4 is a side elevation of the latching and releasing apparatus shown in Fig. 3; and

Fig. 5 is a view partly in section showing the treadles and associated parts of Fig. 4 in plan.

Referring to Figs. 1 and 2, the manually operated latch releasing mechanism is designed for use with foot treadles which do not function to open the press, the foot treadles being either detachable or formed integral with the pedal lever 16''. In this form of the invention the latch 20' is provided with a lug or lateral extension 45 through which the release motion is transmitted to the latch from a lever 46 operated from a point adjacent the table 47, which, it will be understood, is mounted on the frame 10 adjacent the buck. 26' is a projection from the latch 20'

against which a compression spring 25' presses, the other end of the spring engaging a spacer block 24 on the rocking lever 22'. This arrangement maintains constant pressure on the latch, urging it to move forwardly. 28 is a rod threaded 5 at its lower end and engaging a swiveled nut on the rocker lever 22' at 29. 27 is an enlarged head on the upper end of the rod 28 by means of which the rocking lever 22' may be adjusted.

A bracket 48 is mounted on the frame and held 10 in place by screws 49. The lever 46 is pivotally connected at 50 to bracket 48 and is provided with an extension 51 which acts as a stop to downward movement of the lever 46 by abutting the bracket 48. The outer end 52 of the lever 46 is 15 hook shaped for engagement by the fingers of the operator and is located approximately in alignment with the front edge of the press table and a short distance therebelow. The press table is cut away at 53 to allow for insertion of a plate 20 54 which is held to the press table by the screws 55. The plate is provided with a forwardly projecting portion 56 to accommodate the thumb of the operator.

A rod 57 is connected to the lever 46 intermediate the pivot 50 and hooked end 52 at 58 and to the trip crank 59 which is pivotally connected at 60 to bracket 61 which is mounted on an extension 23' of the pivot for the rocking lever 22'. The bracket 61 is prevented from rotation by the set screw 62 or other means engaging between the extension 23' and bracket 61. The upper end of the trip crank 59 is disposed in alignment with or in abutting engagement with the extension 45 when the press is in closed 30 position as shown in Fig. 1, and the shoulder 31' of the latch 20' is moved from engagement with the lug 30' to permit opening of the press by operation of the lever 46.

When the operator presses down with his foot 40 on the treadle 63 which is shown as an integral part of the pedal lever 16'' the lug 30' is brought down along the front face of the latch 20' until it has passed the lower end thereof at which time the latch moves forwardly so that the shoulder 45 31' engages over the lug 30' as shown in Fig. 1. To open the press the operator places his right thumb on the extension 56 of the plate 54 and places his fingers or forefinger under the hooked end 52 of the lever 46 which is raised by a squeezing 50 action between thumb and forefinger. As the lever 46 moves upwardly it exerts a pull through rod 57 on the end of crank 59 turning the same on pivot 60 so that the upper end of the crank presses against the extension or lug 45 55

thus moving the latch 20' backwardly until the shoulder 31' is moved from engagement with the lug 30'. After the latch has been released the operator merely withdraws his fingers from the hook 52 so that the lever 46 will move downwardly under the action of gravity until the extension 51 abuts the bracket 48 at which time the releasing mechanism is in position to again release the latch 20' after the press has been closed.

In Figs. 3-5, I have shown a construction and arrangement of releasing means for the latch comprising a combination of hand lever and foot pedal mechanism, the foot pedal being separate from the main press treadle which operates the toggle mechanism.

Referring to Fig. 3, head 12 is carried by the arms 13, and the buck 11 on frame 10 and other parts of the machine, are of usual construction. The closing movement of the head 12 is initiated by pressure on the treadle 70 which may be an integral part of the foot pedal lever as shown in Fig. 3 or a detachable treadle. The operating lever carries the projecting lug 71 which corresponds to the lug 30 for engagement under the shoulder of the keeper 72 to lock the press closed. Instead of the arrangement of the compression spring to urge the keeper 72 forward, I have shown the keeper as provided with a counter-balance weight 73 which tends to move the keeper forward by swinging movement on pivot 74 extending through the rocking levers 75 which are adjustable by means of the screw 27. The keeper 72 is also provided with a projection or laterally extending lug 76 which is disposed in front of the upper end of the crank lever 77 pivoted at 78 to the releasing pedal 79, which as shown in Fig. 4, is pivoted to the frame at 80 and has at its inner end a counter-balancing weight 81 which tends to maintain the pedal in substantially horizontal position with the stop 81' on the lever abutting a horizontal portion on the frame 10. The movement of the lug 71 under the shoulder of the keeper 72 is effected in the same manner as described in connection with the other figures, it being understood that the counter-balancing weight 73 tends to keep the forward face of the keeper against the projection 71 until the projection has reached the lower end of the face, at which time the keeper will be thrown forward by the weight to engage over the projection. The keeper is moved out of locking engagement with the projection 71 by means of the crank lever 77 which operates in the manner described in connection with the crank 59 of Figs. 1-2, under the action of mechanism now to be described.

To the upper front portion of the frame 10, the bracket 82 is secured by bolts 83. The bracket has upstanding lugs 84 between which is pivoted the hand lever 85 which comprises a stop 86 to engage the front of the bracket 82 and an outwardly extending shank with the finger hook 87 at its forward end. The plate 54' is secured to the front of the table 47' and has the thumb rest 56'. The lever 85 is connected at 88 to the rod 89 which has its other end connected to the crank lever 77 at 90.

In Fig. 4, I have shown the same arrangement as in Fig. 3 with the exception of the hand lever 91 which is of the same construction and arrangement as that shown and described in Fig. 1. Also in Fig. 4, I have indicated the connection 90 as at A, the pivot 78 of the crank lever as B, and the upper end of the crank lever as C, and in connection with the description of the opera-

tion about to be given, reference may conveniently be had to Fig. 4.

The parts are moved to locked position when the treadle lever 70 is depressed so that the extension 71 is brought low enough for the latch 72 to move forwardly on pivot 74 under the action of counterweight 73. To release the latch the operator may place his thumb over the projection 56' with his fingers under the hook on the lever 85 or 91 and raise the lever so that the rod pulling at point A will rock the crank lever on its pivot B to move the end C against the projection 76 to move the latch 72 back until the shoulder is clear of the projection 71.

It will be noted that the crank lever functions as a lever of the first class when release is effected through the hand lever from above as the effort is applied at A and the fulcrum is at B between the point where the effort is applied and the point C where the power is transmitted.

The latch may also be released by depressing the foot pedal 79 which causes the crank lever to act as a lever of the third class for it then fulcrums at A, receives the power at B and transmits the power at C to move the latch 72 out of engagement with the extension 71.

I claim:

1. In combination, an operating lever, latching mechanism therefor, comprising a pivoted latch having a portion disposed beside said operating lever, a projection on said lever, means normally urging said portion of the latch into engagement with said projection, said latch having a recess to receive the projection when the lever is moved to close the press, a crank lever adjacent the operating lever and having one end confronting the latch, a hand lever remote from the latch, a connection between said hand lever and crank lever whereby movement of the hand lever will move the crank lever against the latch to release the projection from engagement with the recess.

2. In combination, a foot-operated lever, latching mechanism therefor comprising a latch cooperating elements on said latch and foot lever operable by movement of the lever in one direction to maintain the lever against return movement, a hand operated lever mounted remote from the latch and foot lever, a foot-operable lever adjacent said first named foot lever, a crank lever carried by said last named foot lever and engageable with the latch to move the same from locking engagement with the first named foot lever, and a connection between said crank lever and hand lever whereby movement of the hand lever will cause the crank lever to engage the latch to move it from locking engagement with the first named foot lever to permit return movement of said foot lever.

3. In combination, a foot operated lever of garment presses and the like, a latch, cooperating elements on the latch and foot lever engageable upon movement of the foot lever in one direction to hold the foot lever against return movement, a releasing lever, two selectively operable actuating means for said releasing lever to actuate said lever and disengage said elements to permit return movement of the foot lever, a point on the releasing lever at which the power is applied from one actuating means serving as a fulcrum point when the releasing lever is actuated by the other actuating means.

4. Latching mechanism for a foot operated lever for garment presses having a work table mounted on the frame of the press comprising a latch, cooperating elements on the latch and

foot lever engageable upon movement of the foot lever in one direction to hold the foot lever against return movement, a hand operated lever mounted on the frame below the work table and provided with a finger gripping surface, a projection on the table in proximity to the finger gripping surface of the hand lever to accommodate the thumb of the operator, a crank lever operable to disengage said cooperating elements to permit 5 return movement of the foot lever, and a connection between the hand lever and crank lever to move the crank lever when the gripping surface of the hand lever is moved toward the thumb accommodating portion of the table to 10 permit return movement of the foot lever.

5. In combination, a foot operated lever of

garment presses having a work table supported on the frame of the press, a latch for the foot lever engageable upon movement of the foot lever in one direction to hold the foot lever against return movement, a pedal lever pivotally mounted adjacent the foot lever, a tiltable member pivoted to the pedal lever and having a portion to disengage said cooperating elements to permit return movement of the foot lever when the pedal lever is rocked on its pivot, a hand lever adjacent the 10 work table, and a connection between said hand lever and tiltable member to move said portion of the tiltable member to disengage said elements upon operation of the hand lever.
